AUXILIARY OILING DEVICE

Marion C. Clarkson, Atlanta, Ga.

Application November 21, 1936, Serial No. 112,132

8 Claims. (Cl. 184—6)

Generically this invention relates to oiling systems but it more especially is directed to an auxiliary system more particularly adapted to automobile engines of the internal combustion type.

5 One of the principal objects of this invention is the provision of an auxiliary oiling system for automobile engines and the like adapted to supply oil under pressure to the cylinder walls, connecting rod bearings, wrist pin bearings and all 10 connections requiring oiling, prior to the starting of the motor and operation of the primary oiling system.

Another important object of this invention is the provision of an auxiliary oiling system for 15 internal combustion engines and the like wherein actuation of the starter button effects operation of the auxiliary system to pre-oil the cylinder walls and other important operating parts prior to the actual starting of the starter mechanism and the motor.

20 A further important object of this invention is the provision of an auxiliary oiling system for automobile engines and the like electrically connected with the starter button and including an auxiliary motor and high speed pump whereby 25 actuation of the starter button effects operation of the auxiliary motor and pump to rapidly deliver oil to the operating parts of the motor in advance of the operation of the starter and automatically closing the circuit to the starter and 30 effecting starting of the engine.

A still further important object of this invention is the provision of an auxiliary oiling system for automobile engines whereby actuation of the 35 starter button initially effects operation of the auxiliary oiling system and successive automatic operation of the starter, engine and primary oiling systems, when the auxiliary system has attained a predetermined oil pressure, without appreciable lag in the starting of the motor during 40 actuation of the starter button.

With these and other objects in view, which will become apparent as the description proceeds, the invention resides in the construction, combination and arrangement of parts, hereinafter more fully described and claimed, and illustrated in the accompanying drawing, in which like characters of reference indicate like parts throughout the several figures, of which:

45 Fig. 1 is a diagrammatic view of my auxiliary oiling system applied to an automobile with the engine partly in section.

Fig. 2 is an enlarged fragmentary view in section of the engine shown in Fig. 1.

50 It is well known that when the conventional

type of internal combustion engine has been stopped the heated lubricating oil quickly flows from the cylinder walls and pistons and when the engine is started the operating parts initially operate, during the time required for the ordinary pumping system to deliver oil thereto, without lubrication. This, of course, is not conducive to long life of such operating parts and especially in cold weather may cause damage thereto by reason of non-lubrication and quick temperature changes. While attempts have been made to remedy this situation, those with which I am familiar have proven deficient in only applying to certain parts or using special types of oil from auxiliary oil supplies and requiring extensive equipment and modification to install, and it was to overcome these and other deficiencies by providing an auxiliary oiling system in conjunction with the primary system, including a high speed auxiliary pump and small motor electrically connected with the starter mechanism and button, so that actuation of the starter button initially effects operation of the high speed pump to deliver oil from the usual oil well or sump to a predetermined point for delivery through the primary system to all operating parts of the engine prior to the starting of the motor, and so designed that when a predetermined oil pressure is reached, an electrical contact will operate to close a circuit through the starter to start the engine and effect operation of the primary system in the usual way, and without maintaining said button depressed appreciably longer than effective to start the motor in the usual manner, that I designed the auxiliary oiling system forming the subject matter of this invention.

In the illustrated embodiment characterizing this invention there is shown an automobile engine A and an auxiliary oiling system B including an operating electrical circuit C. The engine A comprises the conventional block 1, oil well or sump 2, strainer 3, oil pump 4, suction line 5, interconnecting said pump or oil supply and pump 4, and an oil conduit 6 extending from pump 4 to one edge of the block and having mounted therein oil pressure relief valve 7. Spaced upwardly from conduit 6 is a substantially parallelly extending conduit 8 communicating with and discharging into the primary engine oil system, and connected to conduit 6 by conduit 9. Mounted in said conduit or pressure line 6 adjacent to conduit 9 is a check valve 10. A conduit section 11 extending in spaced parallelism with respect to conduit 6 also interconnects conduits 6 and 8 and is normally closed at one end by relief valve 55

7. In alignment with section 11 and with one end communicating with conduit 8 and the other with an oil pressure gauge and also valve tappets, not shown, is oil line 12 and mounted in conduit 5 adjacent lines 11 and 12 is check valve 13, said conduit 8 terminating at one end in chamber 14 of greater diameter than said conduit. Chamber 14 communicates with bore 15 of larger diameter than said chamber and extends to the outer wall 10 surface of the block. Mounted in said bore 15 is a plunger 16 on the stem 17 of which is mounted spring 18. The free end of plunger 17 is adapted to extend through plate 19 forming a closure for bore 15, and suitably secured to said 15 block mounted on plate 19 is a frame 20 suitably secured by set screws 21 formed with a centrally disposed opening 22 in which is suitably mounted insulation block 23 in which is mounted contact member 24 with its inner end extending within frame 20. Said stem 17 is adapted to engage contact 24 when pressure in chamber 14 is applied to plunger 16, stem 17 being normally maintained out of engagement therewith by spring 15, as will hereinafter more fully appear.
- 25 The auxiliary pump 27 and oil line connections will now be described. Communicating with oil sump 2 and strainer 3 is auxiliary suction line 25 extending to a point spaced below relief valve 7 and thence outwardly and with its free end suitably connected as at 26 to auxiliary high speed pump 27 suitably mounted with respect to block 1. Pressure oil line 28 has one end suitably connected to pump 27 as at 29 and the other end suitably extending within block 1 above relief 35 valve 7 to a point spaced from conduit 11 and thence upwardly in parallelism therewith and communicating with chamber 14, as will be apparent. Mounted in said line 25 above strainer 3 is a union 30 so that said pipe line may be 40 broken for cleaning and the like. Suitably mounted adjacent pump 27 and connected thereto by drive shaft 31 is an electric motor 32 for driving said auxiliary high speed pump, as and for a purpose directly more fully appearing.
- 45 The circuits by which the auxiliary motor 32 and starter 33 are operated will now be described. Battery 34 is grounded as at 35 and from said battery electric current is adapted to flow through conductor 36 to contact point 37 and from contact point 38 through conductor 39 to motor 32 and conductor 40 to ground, completing the circuit through motor 32 when starter button 41 is brought into bridging engagement with contacts 37 and 38 to close said circuit, and operate 50 high speed pump 27 to draw oil from sump 2 through suction line 25 through pump 27 and then said oil is directed through pressure line 28 to chamber 14, through valve 13 and conduit 8 to the primary engine oiling system, not shown,
- 55 for distribution of the oil to the cylinder walls, main bearings, connecting rod bearings, wrist pin bearings and other vital operating parts of the engine, as will be well understood. This operation, of course, precedes the operation of the 60 primary oil pump 4, as will directly appear.
- When a predetermined pressure has been built up in chamber 14, plunger 16 will overcome the tension of spring 18 and move stem 37 to engage contact member 24, which will complete the circuit 65 through conductor 42 to relay 43, conductor 44, to battery 34 to ground, thus completing a ground circuit and from conductor 44 through conductor 45, and as core 46 is energized contact 47 is moved into engagement with contact 48, closing the circuit from the battery through con-

ductor 49, and starting mechanism 33, to ground 50, thus starting the engine and operating primary motor 4 to draw oil from sump 2 through suction line 5, pump 4, pressure line 6, conduit 9 to conduit 8 and, thence through the primary 5 oiling system heretofore referred to and, after the motor is started button 41 is released, opening the circuit to motor 32 which stops pump 27, at which moment valve 13 closes, and the oil in said chamber and line 28 drains back through pump 27 relieving the pressure in said chamber and allowing spring 18 to move plunger 16 to its initial position, opening circuit 42 and breaking the relay circuit to starter 33 and stopping the same, as will be well understood.

15 The operation of the device will be sufficiently clear from the above description as to render further explanation of the operation of the auxiliary system unnecessary, except it will be noted that all the above operation takes place during the holding of starter button 41 in engagement with contacts 37 and 38 and without any apparent lag in the starting of the motor, so that in so far as it is apparent to the operator, actuation of starter button 41 effects starting of the 25 motor in the usual manner.

When starter button 41 is depressed, bridging contacts 37 and 38 and effecting starting of motor 32, high speed pump 27 quickly delivers oil through suction line 25, pump 27, pressure line 28, 30 chamber 14, conduit 8 to the primary engine oil system, and as soon as a predetermined pressure is built up in chamber 14, and which may be limited to any amount of operating pressure desired by the tension of spring 18, the circuit is 35 closed through relay 43 to storage battery 34, thus energizing the core and closing the contacts of said relay 43, which completes the circuit from battery 34 through the starter 33, operating said starter to effect starting of the engine and bringing into operation the primary oiling system as above described, and instantly the starter is in operation the pressure on starter button 41 is released, thereby opening the circuit and effecting stopping of the auxiliary motor and starter, as 45 heretofore described.

From the above it is apparent that the operating parts of the motor which become dry when the motor is cut off will, instead of having to run without lubrication pending the delivery of oil 50 through the primary oiling system after the motor is started, be pre-oiled before movement is imparted to said parts by starting of the engine by the starter, and, therefore, damage to such parts is prevented and their length of life and 55 smooth running qualities greatly increased.

It will be apparent that I have designed an auxiliary oiling system, including electrical circuit arrangement controlled by the starter button adapted to operate in advance of the primary oiling system, simple in construction, applicable to existing engine structures with slight modification according to the particular type of engine, manufactureable at a minimum of cost, and efficient for the purposes intended.

65 Although in practice I have found that the form of my invention illustrated in the accompanying drawing and referred to in the above description as the preferred embodiment, is the most efficient and practical, yet realizing the conditions concurrent with the adoption of my invention will necessarily vary, I desire to emphasize that various minor changes in details of construction, proportion and arrangement of parts, may be resorted to within the scope of the ap- 75

pended claims without departing from or sacrificing any of the principles of the invention.

Having thus described my invention, what I desire protected by Letters Patent is as set forth in the following claims:

- 5 1. In combination with an internal combustion engine including a primary and an auxiliary oiling system, of an electrical starter mechanism for the engine, an electro-mechanical pumping mechanism for rendering the auxiliary oiling system operative until a predetermined oil pressure has been attained, an electro-mechanical means controlled by the pressure existing in the primary and auxiliary systems and co-acting with the starter to effect operation of the latter, when said predetermined oil pressure has been reached.
- 10 2. In combination with an internal combustion engine including a primary oiling system, of an auxiliary oiling system co-acting with said primary system and including a pressure chamber, an electrical starter mechanism for the engine, an electrical mechanism for rendering the auxiliary oiling system operative until a predetermined pressure is reached, an electro-mechanical means controlled by the pressure in said chamber and co-acting with the starter to effect its operation.
- 15 3. In combination with an internal combustion engine including a primary oiling system, of an auxiliary oiling system co-acting with the primary system and including a pressure chamber and high speed pump, an electrical starter mechanism for the engine, an electrical mechanism for operating said pump and rendering the auxiliary oiling system operative until a predetermined oil pressure is obtained in said chamber, an electro-mechanical means including a moveable contact element controlled by the pressure in said chamber and co-acting with the starter mechanism to effect its operation.
- 20 4. In combination with an internal combustion engine including a primary oiling system, of an auxiliary oiling system co-acting with the primary system and including a high speed pump and motor, an electrical starter mechanism for the engine, an electrical mechanism connected to said motor and rendering the auxiliary system operative until a predetermined oil pressure is reached in said systems, an electro-mechanical means including a pressure controlled contact element and co-acting with the starter mechanism to effect its operation when said predetermined oil pressure has been reached.
- 25 5. In combination with an internal combustion engine including a primary oiling system, of an auxiliary oiling system coacting with the primary system and including an oil pressure chamber, high speed pump and electric motor for driving the pump, an electrical starter mechanism for the engine, an electrical mechanism including a pump
- 30 6. In combination with an internal combustion engine including a primary oiling system, of an auxiliary oiling system associated with the primary system, said auxiliary oiling system associated with and including a pump, a motor for driving the pump, and an electrical starting mechanism for the engine including the motor of said pump, a pressure controlled electro-mechanical means normally excluding the starting mechanism from the electrical starting circuit, said electro-mechanical means being controlled by the pressure in the combined primary and auxiliary oiling systems to include the starting mechanism in the starting circuit when a predetermined pressure has been obtained in the oiling systems.
- 35 7. In combination with an internal combustion engine including a primary oiling system, of an auxiliary oiling system associated with the primary system, said auxiliary system including a pressure chamber, a pump, a motor for driving the pump, and an electric starting mechanism and circuit for the engine and including the motor of said pump, a pressure controlled electro-mechanical means normally excluding the starting mechanism from the starting circuit, said electro-mechanical means being controlled by the oil pressure in said pressure chamber to include the starting mechanism in the starting circuit when a predetermined pressure has been obtained in said pressure chamber.
- 40 8. In combination with an internal combustion engine including a primary oiling system, of an auxiliary oiling system associated with the primary system, said auxiliary system including an oil pressure chamber, a pump, a motor for driving the pump and an electric circuit and starting mechanism for the engine, and including the motor of said pump, a pressure controlled electro-mechanical means including a movable contact associated with said pressure chamber normally excluding the starting mechanism from the starting circuit, said movable contact and electric mechanical means being controlled by the pressure in said chamber to include the starting mechanism in the starting circuit when a predetermined pressure has been obtained in said chamber, whereby the auxiliary oiling system is excluded and operation of the engine and the primary oiling system is effected.
- 45 55 60
